UNITED STATES PATENT OFFICE.

ELMER WILLIAM ADAMS, OF NORTH TOPEKA, KANSAS.

SLIDING GATE-LATCH.

932,232.

Specification of Letters Patent. Patented Aug. 24, 1909.

Application filed November 16, 1908. Serial No. 462,943.

To all whom it may concern:

Be it known that I, ELMER WILLIAM ADAMS, a citizen of the United States, residing at North Topeka, in the county of 5 Shawnee and State of Kansas, have invented certain new and useful Improvements in a Sliding Gate-Latch; and I do declare the following to be a full, clear, and exact description of the invention, such as will enable 10 others skilled in the art to which it appertains to make and use the same.

This invention relates to an improved sliding gate latch and the object thereof is to provide a simply constructed and efficient 15 device of this character especially adapted for application to a gate composed of metal tubing.

With this and other objects in view, the invention consists of certain novel features 20 of construction, combination and arrangement of parts as will be more fully described and particularly pointed out in the appended claims.

In the accompanying drawings, Figure 1 25 represents a side elevation of a gate with this improved latch applied; and Fig. 2 is a longitudinal vertical section of the latch detached. Fig. 3 is a horizontal section of the latch taken on line 3—3 of Fig. 2.

30 In the embodiment illustrated, a gate 1 is shown composed of tubular metal bars and of any desired or ordinary construction. A latch or sliding bolt 2 is housed within a casting 3 having a casting 4 extending at 35 right angles thereto and U-shaped in cross section. This casting 4 is secured to the upright tubular member at the front of the gate by bolts or any other suitable means. The casting 3 is also preferably U-shaped in cross 40 section and is provided at its outer free end with an integral closure 5 with an aperture therein in which the bolt 2 is mounted to slide. This bolt is preferably provided midway its length with an annular shoulder 6 45 and a coil spring 7 is mounted on said bolt between said shoulder and the rear end of closure 5 of the casting 3 and tends to normally hold said bolt in projected locked position. A transverse aperture is formed in the 50 upright member of the gate to receive and permit the bolt 2 to slide therethrough and the casting 4 which extends around this member and projects on opposite sides of the

aperture serves to reinforce the pipe where it is weakened by the bolt hole. To the rear 55 end of the bolt 2 is fastened a chain 8 or other flexible element which is secured at its opposite end to a fixed portion of the gate and is designed to be grasped by the operator and pulled laterally which causes the bolt 2 to 60 move back laterally and become disengaged from the gate post.

From the foregoing description, taken in connection with the accompanying drawings, the construction and operation of the 65 invention will be readily understood without requiring a more extended explanation.

Various changes in the form, proportion and the minor details of construction may be resorted to without departing from the principle or sacrificing any of the advantages of the invention as defined in the appended claims.

I claim as my invention:

1. In a sliding gate latch, the combination 75 of a T-shaped casting U-shaped in cross section with the head thereof opening outwardly and the stem opening at one side, an apertured closure arranged at the free end of said stem, a spring pressed bolt mounted to 80 slide within said stem and project through the aperture in said closure, and means for connecting said projected end to a fixed object to provide for the withdrawing of the bolt against the tension of its spring. 85

2. In a sliding gate latch, the combination of a casting U-shaped in cross section and provided with means for securing it to the upright of a gate, a hollow member extending at right angles to the rear face of said casting and having its rear end closed and its front end communicating with said casting, a bolt housed within said hollow member and extending through an aperture in the closed end thereof and projecting beyond said casting, and a coil spring mounted on said bolt within said hollow member and adapted to hold the bolt in projected position. 95

In testimony whereof I have hereunto set my hand in presence of two subscribing witnesses.

ELMER WILLIAM ADAMS.
